MULTIPOLE MAGNETO ROTOR CHARGING
BLOCK

Benjamin Rozett, Chicago, Ill., assignor to Joseph Weidenhoff, Incorporated, a corporation of Illinois

Application July 14, 1948, Serial No. 38,670

2 Claims. (Cl. 175—21)

1

This invention relates to multi-pole magneto rotor charging adapter blocks.

One feature of this invention is that it enables a simple two-pole magnetizer, perfectly balanced magnetically, to recharge multi-pole magneto rotors, whether of an even or odd number of poles; another feature of this invention is that it ensures uniform flux remnance, a very necessary characteristic in a properly charged rotor; another feature of the particular blocks disclosed herewith is that pairs of cooperating blocks are identical and can be made with one casting; and yet another feature of this invention is that these particular blocks, with the pole portions at an angle to the plane of the foot portion, provide greater flux carrying area and, with proper design, a minimum reluctance to flux flow. Other features and advantages of this invention will be apparent from the following specification and the drawings, in which:

Figure 1 is a side elevational view of a two-pole magnetizer and a pair of blocks embodying my present inventions being used to charge a four-pole rotor; Figure 2 is a top plan view of the structure shown in Figure 1; Figure 3 is a transverse sectional view along the line 3—3 of Figure 1; Figure 4 is a side elevational view of one of the blocks, the left hand one as viewed in Figure 1; and Figure 5 is a sectional view along a plane through the rotor axis, this view being along the line 5—5 of Figure 3.

In ignition circuits for certain types of relatively high powered internal combustion engines there is an increasing trend toward multi-pole rotors in the magnetos. In a high powered aircraft engine of the radial type, fourteen cylinders are quite common, and if these are handled by a single magneto, the magneto must develop seven ignition impulses for each shaft rotation. This would obviously require an unduly high rotor shaft speed of rotation when the engine is operating anywhere near its maximum speed, with very undesirable bearing and lubrication problems being presented in the magneto, if only a two-pole rotor were used. The use of a four-pole rotor cuts the required speed of rotation in half, and such rotors are very common. Even a greater number of poles are frequently used.

Such rotors not only have to be charged initially, but also have to be relatively frequently charged throughout their life, as a service operation, to maintain the rotor pole strength at the desired level. This has always heretofore been done by multi-pole magnetizers having the same number of wound poles as there are poles in the

2

rotor to be charged. Such magnetizers are relatively expensive, because of the large amount of wire, iron and labor required to provide four or six wound poles of great strength, for example, but also are extremely difficult to properly balance magnetically with the precision desirable. Merely providing the same number of turns on each of the magnetizer coils by no means insures the same flux density in a given pole face area, since variations in the winding, the material of the wire and pole piece enter into the balance. A two-pole magnetizer, on the other hand, is inherently perfectly balanced, since while it has two windings both contribute to a single magnetic circuit and the flux density in that portion of the magnetic circuit used for magnetizing a rotor is a summation of the contributions of the two coils, so that even substantial differences therein in no way disturb charging conditions.

In order to enable the relatively simple and inherently perfectly magnetically balanced two-pole magnetizer to be used to charge multi-pole magneto rotors, I have devised adapter blocks having characteristics here disclosed. These blocks are of magnetic material and each has a portion in good magnetic relationship with the faces of the poles of the magnetizer, each block further having two pole portions adapted to receive the rotor therebetween, the pole portions of the two blocks being so constructed and arranged that they are interleaved and symmetrically spaced about the rotor during charging, with all portions of each block being spaced from all portions of the other block at least several times the spacing between the rotor and the adjacent faces of the pole portions of the block to insure concentration of the flux into and through the rotor poles.

Referring now more particularly to the embodiment of the invention illustrated herewith, a two-pole magnetizer of a type now on the market is illustrated as having a base portion 10, wound magnetizing coils 11 and 12, and pole pieces 13 and 14 providing pole faces 13a and 14a in the same plane. During magnetizing procedure the coils would be energized from an appropriate source of current and strong magnetic forces of opposite polarity developed at the pole faces 13a and 14a, the poles and base of course being of magnetic material, as cast steel. Further description of the magnetizer is believed unnecessary, as the particular device shown is available commercially and well known in the field.

Turning now more particularly to the adapter

blocks, these are here identified in general as A and B. While identical devices in the particular form illustrated, it will be understood that they must always be used in pairs appropriate to the rotor size and number of poles, and that it is unnecessary that they be identical.

Since the particular embodiment of my invention illustrated herewith has identical blocks, only one such block will be described in detail, except insofar as may be necessary to bring out the combined operation of the devices. Referring now more particularly to Figures 3, 4 and 5, it will be seen that the block A has a main body portion here identified as 20 carrying, or more properly speaking having integral therewith, the two pole portions 21 and 22. The size of the blocks is of course determined by the size, and particularly of the diameter, of the rotor to be charged, one pair of blocks which I have built and which are of representative size for conventional magneto rotors having body portions $4\frac{1}{2}$ inches high by 4 inches wide, with their thickness and the dimensions of the pole portions in the proportions illustrated in the drawings.

The body is provided with a foot portion at the lower end, which may extend for example about a half inch below the lower portion 22, this portion being here identified as 20a. This foot portion has a flat bottom, a plane machined surface here identified as 20b adapted to make good magnetic contact with the plane pole surface 13a of the magnetizer, so that a flux path of low reluctance and high flux carrying capabilities is provided into and through the body portion of the block.

The pole portions 21 are of identical configuration and symmetrically spaced with respect to the center of a relatively large hole or opening 23 through the block.

As may be best seen in Figures 3 and 5, the magneto rotor comprises a shaft portion here identified as 24 and a cylindrical body or rotor portion proper here identified as 25, the rotor illustrated having four pole portions identified as 25a, 25b, 25c and 25d. The adapter blocks are designed for a given size of rotor, and the pole portions are provided with machined pole faces (sections of a cylindrical surface), here identified as 21a and 22a. These are adapted to lie closely adjacent the pole faces of the rotor when it is between the pole portions of the block, with a very small clearance between these adjacent faces, preferably not over $\frac{1}{1000}$ of an inch. The inner surfaces of the pole portions are initially cast in such manner as to be closer to the axis of the opening 23 than illustrated, and are then machined in a step cutter and miller to provide the desired finished cylindrical surfaces and the step or shoulder on each pole portion, here identified as 21b and 22b which provide stop means for engaging the rotor and properly locating it with respect to the block during charging, as may be best seen in Figure 5.

This figure illustrates the arrangement when the blocks are in operative position and charging a rotor. The blocks are arranged with the flux carrying fingers or pole portions facing toward each other and at least partly interleaved, so that the rotor is surrounded by symmetrically spaced pole faces of alternate polarity. By bringing the blocks toward each other until the shoulders or stop portions engage the edges of the rotor poles the parts are properly positioned. It will be noted that in this charging position the rotor shaft is substantially spaced from any flux

carrying part of the blocks and, as may be best seen in Figure 3, the pole portions of opposite blocks are sufficiently narrow (in relation to the rotor diameter) to be spaced from each other many times the spacing between the pole faces and rotor poles. Similarly, as may be best seen in Figure 5, the stop means provided by the shoulders results in spacing of the ends of the pole portions a substantial distance from the opposite block face. This, together with the provision of the foot spacing the pole portions well above the magnetizer pole faces, results in a construction and arrangement concentrating flux energy through the rotor poles and allowing substantially no flux leakage through other paths. This not only results in the maximum rotor magnetization for a given magnetizer strength, but also prevents magnetizing of the shaft (if of magnetic material) and other undesired stray magnetizations.

The shoulders 21b and 22b should preferably be quite shallow, if of the same magnetic material as the block illustrated, to prevent entry of too much flux from the side rather than the periphery of the rotor. I contemplate providing blocks for handling almost all conventional four-pole rotors from a single casting by machining the pole portion openings of appropriate sizes, but it will be understood that sleeves or other inserts, either as permanent parts of the blocks or as replaceable parts can be used to handle different sized rotors. Similarly, the stop means may be provided by non-magnetic means if desired, as a brass sleeve, or entry of flux from the side edge of the rotor minimized by the use of a spacer washer of fiber or other non-magnetic material.

One of the most important features of my adapter blocks is location of the pole portions or fingers with their plane at an angle of 45° to the plane of the foot portion of the device, as may be best seen in Figure 3. This not only provides greater flux carrying capacity in the pole portions for a given adapter block size, but also has the very great advantage of enabling a single casting, in the case of work on a four-pole rotor, to provide the two cooperating blocks. The same casting provides one block, as the block A, having the plane of its pole portions running from lower left to upper right as the parts are viewed in Figure 3, and at the same time a cooperating block which, because it is facing in the opposite direction, has the plane of its pole portions 21' and 22' running symmetrically from lower right to upper left as viewed in such picture. In addition to its manufacturing convenience, the location of the pole portions at a 45° angle insures complete uniformity of magnetizing and of remnance in the rotor pole portions. Since the pole faces of the portions 21 and 22 would be of a given polarity, as north, and those of the other block of the opposite polarity in the case of a four-pole rotor, the fluxes divide and each rotor pole is subjected to an equal total quantity of flux, the total flux through each rotor pole being the sum of a longer magnetic path and a shorter magnetic path in each case. Rounding of all corners and junctures improves the flux carrying capabilities of the blocks.

It will be understood that, while adapter blocks are illustrated for charging a four-pole rotor, my invention is applicable to the charging of six or eight-pole rotors, or even to rotors with an odd number of poles, although in such cases the blocks, with their requisite number of pole por-

tions, would have to be cast and machined independently. It is also to be understood that charging may be done in any conventional manner with these adapter blocks, proceeded if desired by demagnetizing forces. My blocks provide means for getting the magnetic forces in the magnetizer, of whatever characteristic, into the poles of a multi-pole rotor with complete uniformity of distribution of flux and forces, and therefore of remnance, from a simple two-pole magnetizer.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. An adapter block for charging a multi-pole rotor from a two-pole magnetizer, said block comprising a foot portion with a plane surface adapted to make contact with a pole face of the magnetizer and a body portion having two spaced pole portions projecting therefrom in the same direction generally parallel to said plane foot surface and having spaced confronting pole faces adapted to receive the rotor therebetween, a plane through the longitudinal axes of said two pole portions lying at an angle of forty-five degrees to the plane of said foot portion surface.
2. An adapter block for charging a multi-pole

rotor from a two-pole magnetizer, said block comprising a main body portion having extending therefrom a foot portion with a plane surface adapted to make contact with a pole face of the magnetizer, two spaced pole portions extending from the body portion in the same direction generally parallel to said plane foot surface and having spaced confronting pole faces adapted to receive the rotor therebetween, a plane through the longitudinal axes of said two pole portions lying at an angle of forty-five degrees to the plane of said foot portion surface, stop means on the pole portions for engaging the rotor, and an opening in the body portion between the pole portions for receiving the shaft of the rotor and having a diameter substantially greater than that of any shaft to be received.
